UNITED STATES PATENT OFFICE.

HARRY L. AYER, OF BOSTON, ASSIGNOR TO THE CARLETON COMPANY, OF MALDEN, MASSACHUSETTS.

DESIGN FOR A BAROMETER-FRAME.

SPECIFICATION forming part of Design No. 22,508, dated June 6, 1893.

Application filed March 18, 1893. Serial No. 466,721. Term of patent 3½ years.

To all whom it may concern:

Be it known that I, HARRY L. AYER, of Boston, in the county of Suffolk and State of Massachusetts, have invented a certain new and original Design for a Barometer Frame or Support, of which the following is a specification.

The drawing accompanying this specification and forming a part hereof is a front view of my design.

The leading feature of my design is the full front figure of an owl with folded wings and wide open eyes, a rectangular bar in the beak of the owl extending in a horizontal line on both sides of the beak and a piece of a branch of a tree upon which the owl is perched.

In the drawing *a* designates the body of the owl, and *b* the wings which are folded to the sides of the body.

c designates a piece of a branch or twig of a tree upon which the owl is perched, parts of its claws *d* being exposed to view.

e *e* designate the eyes, which are wide open; and *f* is the beak in which a rectangular bar *g* is shown as being held.

What I claim is—

The design for a barometer frame or support, substantially as herein shown and described.

In testimony whereof I have signed my name to this specification, in the presence of two subscribing witnesses, this 30th day of January, A. D. 1893.

HARRY L. AYER.

Witnesses:

OSCAR A. RICE,
CHAS. C. AYER.
